CLAIM

The ornamental design for a 3D printer cartridge assembly packaging, as shown and described.

DESCRIPTION

FIG. 1 illustrates an elevated left-side perspective view of the 3D printer cartridge assembly packaging;

FIG. 2 illustrates an elevated right-side perspective view of the 3D printer cartridge assembly packaging;

FIG. 3 illustrates a first bottom perspective view of the housing of the 3D printer cartridge assembly packaging;

FIG. 4 illustrates a second bottom perspective view of the housing of the 3D printer cartridge assembly packaging;

FIG. 5 illustrates a front view of the 3D printer cartridge assembly packaging;

FIG. 6 illustrates a posterior view of the 3D printer cartridge assembly packaging;

FIG. 7 illustrates a top view of the 3D printer cartridge assembly packaging;

FIG. 8 illustrates a bottom view of the 3D printer cartridge assembly packaging;

FIG. 9 illustrates a left-side view of the 3D printer cartridge assembly packaging; and,

FIG. 10 illustrates a right-side view of the housing of the 3D printer cartridge assembly packaging.

1 Claim, 7 Drawing Sheets
